(57) **CLAIM**

I claim the ornamental design for a pickup truck, as shown and described.

DESCRIPTION

FIG. 1 is a left side view of the pickup truck.

FIG. 2 is a right side view of the pickup truck.

FIG. 3 is a back perspective view of the pickup truck.

FIG. 4 is a front perspective view of the pickup truck.

FIG. 5 is a top view of the pickup truck; and,

FIG. 6 is a front view of the pickup truck.

The application is directed to a pickup truck. The bottom view of the pickup truck is not a part of the claimed design.
